UNITED STATES PATENT OFFICE.

EDWIN E. WOLF, OF NEW YORK, N. Y.

DESIGN FOR A DRESS.

Application filed January 26, 1924. Serial No. 8,424. Term of patent $3\frac{1}{2}$ years.

To all whom it may concern:

Be it known that I, EDWIN E. WOLF, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by means of an ornamental substantially rectangular insert at the front and immediately below the neck, together with an ornamental band near the bottom of the blouse of the dress having the same general appearance as the rectangular square. The design is also distinguished by

means of the skirt having spaced sections of ornamental plaiting extending from the top to the bottom of the skirt.

Figure 1 is a front view of a dress, showing my new design.

Figure 2 is a rear view of the dress shown in Figure 1.

Figure 3 is an enlarged fragmentary view showing part of the ornamental square of the upper part of the dress.

Figure 4 is an enlarged fragmentary view of part of the ornamental band shown in Figures 1 and 2.

I claim:

The ornamental design for a dress, substantially as shown and described.

EDWIN E. WOLF.
